UNITED STATES PATENT OFFICE.

EDGAR P. COOK, OF GRANVILLE, OHIO.

HIGH-POWER AIR-RIFLE.

1,045,373.

Specification of Letters Patent.

Patented Nov. 26, 1912.

Application filed March 23, 1912. Serial No. 685,797.

To all whom it may concern:

Be it known that I, EDGAR P. COOK, a citizen of the United States, residing at Granville, in the county of Licking and 5 State of Ohio, have invented certain new and useful Improvements in High-Power Air-Rifles, of which the following is a specification, reference being had to the accompanying drawing.

10 This invention relates to ordnance apparatus and more particularly to that class known as air guns, or rifles.

The main object of this invention is to produce an air-rifle which will be of high 15 power and sufficiently powerful to be used for general sporting purposes, without requiring the use of gun powder or other explosives to give the bullets used the necessary velocity.

20 Another object of this invention is to have the rifle constructed, so that it may be manipulated with ease and at the same time be provided with means for adjusting parts of the rifle, whereby its sensitiveness of 25 action may be varied to suit the conditions arising or the person using it.

A further object is to provide a high power rifle which will be comparatively noiseless and smokeless.

30 A still further object is to have the parts of the rifle easily accessible for inspection, repair and other purposes.

Other objects of this invention will become apparent as it is more fully set forth.

35 The rifle referred to in this application consists in general of a barrel arranged to receive the bullet and a casing properly attached to the barrel and provided with the general parts of the device. The working 40 parts consist of a movable chamber having a reduced opening arranged to align with the base of the barrel so that the blast of air forced through the chamber by a plunger provided therein, will force the bullet from 45 the rifle in the manner desired. A suitable power spring, together with catches and trigger mechanism are provided for the proper working of the plunger and air chamber, as will be more fully described in 50 a later part of the specification.

In the accompanying drawings which illustrate an embodiment of this invention, Figure 1, represents a side elevation of a gun or rifle embodying this invention. Fig. 55 2, is a longitudinal section through the rifle shown in Fig. 1, showing the working parts

on a slightly enlarged scale. Fig. 3, is a longitudinal section though a preferred form of bullet, to be used in this rifle. Fig. 4 is a detail in perspective of a traveling 60 air-chamber used in the rifle. Fig. 5, is a detail section showing the working parts in loading position, and the relative positions of the power arms, and air chamber to permit the bullet to be placed in the bore of the 65 rifle, the trigger mechanism is not shown as it is similar to that shown in Fig. 2. Fig. 6, is a detail section, showing the bullet and working parts in shooting or cocked position. Fig. 7, is a detail section similar to 70 Fig. 6, but of slightly modified construction. Fig. 8 is a detail of a safety device used in the rifle. Fig. 9 is a transverse section of the rifle on the line 9—9, of Fig. 2.

Similar reference characters refer to similar parts throughout the drawings.

In the construction shown in the drawings, 1 represents the stock or shoulder portion of the rifle and may be of any conventional design, and 2, is the trigger frame or 80 protector, and is suitably attached to the rifle. The casing containing the main working parts of the rifle is designated by the reference numeral 3, and the barrel by 4. The casing 3 is in general, cylindrical, except at the portion 5, adjacent to the stock, where it is arranged for the trigger mechanism, and other parts working in connection therewith. The casing adjacent to the barrel 4, is provided with a recess 6, for the 90 bullet, which is slightly larger than the latter and the bore 7 of the barrel, in order to permit it to be easily placed therein, and a suitable opening 8 is provided in the casing close to the recess, so that the bullet can 95 be easily placed in the rifle.

An air chamber 9, is provided in the casing and is arranged to slide easily in it. Its front portion 10, is restricted inferiorly to a conical shape, so that the air blast will be 100 more suitably directed to the recess 6, when the gun is fired. A plunger 11, having a stem 12 is disposed in the air chamber 9, and closely fits the same, so that there will be but a slight leakage of air, when it is forced 105 into the chamber 9. A strong coiled spring 13, is positioned on the stem 12, and connected to it and the stock of the gun, so that the plunger will be actuated by it, when released from the catches 14, by the trigger 110 mechanism 15. The catches or sears 14, are fulcrumed on the pivot 16, in the casing 3,

and are provided with hooked ends 17, which engage on lugs 18, provided on the stem referred to. Portions 19, of the catches are extended toward the adjusting screws 20, of the trigger mechanism, so as to be actuated thereby, and springs 21, are provided for the purpose of keeping the catches suitably positioned for their work. The trigger proper is indicated at 22, and is attached to a body piece 23, which is pivotally held to the portion 5, of the casing and restricted in its downward movement by a pin 24. Fas-
5 tened to the portion 10, of the air chamber is a lug or projection 25, to which a lever 26, has one of its ends pivoted and which in turn has its other end pivotally connected to a draw bar 27, which is pivotally connected to the portion 5 of the casing as is clearly shown in the drawings. The draw bar 27, and lever 26, afford a powerful means of
10 returning the power spring to its cocked position, and for moving the other parts connected therewith. A handle 28 is provided on the draw bar 27, so that the latter may be easily manipulated, and a suitable catch
15 29 is provided for keeping it positioned horizontally when it is moved adjacent to the barrel and casing.

Referring to Fig. 3, which shows a detail
30 of a preferred form of bullet, 30 indicates the bullet proper, and 31, flanges on its rear portions adapted to engage in the rifling curves in the barrel should same be provided. The flanges 31, are provided on the
35 front portion of the bullet for a similar purpose.

In Fig. 7, the plunger is provided with a casing 32, instead of a stem, and which slides over casing 34, which contains the
40 power spring for actuating the plunger. The casing 32 is provided with slots 36, which slip on the guides 35, which are on the casing 34, in this modification. The lugs 18, are similar to those described for the
45 previous modifications and for the same purpose. The casing 34, serves for keeping the power spring 13, properly positioned in the casing and also protect it from injury.

In operating the gun the operator first
50 pulls down on the handle 28, and gets the working parts in the position shown in Fig.
5, then insert the bullet in the recess 6, at the same time the lugs 18, are caught on the catches 14, and the spring 13, is held under
55 tension within the casing 34, until the trigger mechanism releases it. After the bullet is placed in position, the drawbar, its handle and the lever 26, are connected with it, and returned to their horizontal positions as
60 shown in Figs. 6 and 7. This action places the air chamber in position so that the plunger will compress the air in it, and send the latter against the bullet in the recess 6, when the trigger is pulled and the spring 13,
65 forces the plunger forward. It is of course

understood that the rifle may be supplied with the usual attachments provided for the purpose of assisting in aiming, etc., without referring to such in detail.

The attachment 37, is a device for preventing the movement of the catches, or sears, as they are often called and it consists in general of a lever pivoted in the casing and provided with a lug 38, which comes in contact with the projection 19, on the catch or sear. One end 39, of the attachment is knurled so that it may be easily moved, and held so as to prevent the trigger mechanism for setting the gun off until desired. 40 is a slot provided in the casing 3, in order to permit the part 25, to reciprocate therein, in the desired manner.

Obviously while only two modifications of this device are shown in the drawings, it is not desired to limit this application for patent to that particular construction or in any other way otherwise than limited by the prior art as many modifications of this invention may be made without departing from the principles thereof and coming within the scope of the appended claims.

Having thus described the invention, I claim:

1. In a device of the class described the combination of a gun-barrel having recess therein for the reception of bullets, a casing for holding the barrel provided with a chamber therein alined with the gun-barrel, a hollow air-chamber reciprocatable in and closely fitting said first mentioned chamber, a head for said air-chamber having a converging interior passage alined with said recess, a lug projecting from said head and the casing, a plunger closely fitting in said air-chamber and reciprocatable therein, a stem for said plunger having an engaging lug thereon, a coiled spring for actuating the plunger against the air-chamber, a casing for receiving said spring rigidly secured to the gun casing, said last mentioned casing being arranged to closely fit in the air chamber, and trigger mechanism for said moving parts, and toggle levers attached to the lug on said head for pulling back the air-chamber, plunger and spring into cocked position.

2. In a device of the class described, the combination of a casing having a recess therein for the reception of bullets and an opening adjacent to the recess whereby the bullets may be placed therein from the interior of the casing, an air chamber having a hole therein alined with said recess, said air chamber being movable in said casing to and from said recess whereby said opening may be covered or uncovered by the same, and the hole brought adjacent to the recess, a resilient member for compressing the air in said chamber and forcing it through said hole, trigger means for controlling the

plunger, and toggle mechanism secured to the casing and chamber for moving the latter and placing said plunger under the control of the trigger means, and means for 5 guiding said plunger and limiting the movement of the toggle mechanism.

3. In a device of the class described, the combination of a casing having a recess therein for the reception of bullets and an 10 opening adjacent to the recess whereby the bullets may be placed therein from the interior of the casing, a fluid chamber having a hole therein alined with said recess, said chamber being movable in said casing to 15 and from said recess whereby said opening may be covered or uncovered by the same and the hole brought adjacent to the recess,

a resilient member for compressing the fluid in said chamber and forcing it through said hole, trigger means for controlling the plunger, and toggle mechanism secured to the casing remote from the recess and to the chamber adjacent the hole for moving the latter and placing said plunger under the control of the trigger means, means for 20 guiding said plunger, and adjusting means for the trigger means. 25

In testimony whereof I hereunto affix my signature in the presence of two witnesses.

EDGAR P. COOK.
